UNITED STATES PATENT OFFICE

2,544,956

SPRING GATE FLUX DAM FOR
GALVANIZING KETTLES

Michael Hayes, Dundalk, Md., assignor to Rheem
Manufacturing Company, San Francisco, Calif.,
a corporation of California

Application July 16, 1948, Serial No. 39,128

8 Claims. (Cl. 91—12.5)

1

This invention relates to apparatus for use in the plating or coating of articles by the submersion of the articles in a bath of plating or coating medium, and, while not necessarily limited thereto, is particularly adapted to apparatus for use in the galvanizing of ferrous articles.

In the galvanizing of ferrous articles, the articles, after preliminary treatment, are submerged in a bath of molten zinc for a length of time sufficient to allow a zinc coating of the desired thickness to form thereon. Ordinarily the portion of the bath of molten zinc into which the articles are submerged is covered with a supernatant flux layer, such as a layer of ammonium chloride or zinc ammonium chloride, which gradually will liberate chlorine and serve to provide the final cleaning of the surfaces of the articles as they are lowered therethrough into the molten zinc. However, the surface of that portion of the bath from which the articles are withdrawn should be maintained free from flux, for otherwise particles of the flux would adhere to the coated articles as they are withdrawn and leave them with an unsatisfactory and wholly undesirable surface finish.

Heretofore a dam has been placed across the top portion of the zinc kettle to maintain the flux at that end of the bath of molten zinc where the articles are submerged, and the articles have been so manipulated by the operators as to cause them to pass beneath the dam and into the bright end of the kettle. The application of Richard S. Rheem and Robert D. Patterson, Ser. No. 578, filed January 5, 1948, now Patent No. 2,520,658, discloses a method and apparatus for galvanizing ferrous articles in which the articles to be galvanized are supported by hooks from a continuously-moving overhead conveyor which has a path of travel such that the suspended articles are automatically lowered through the flux layer into the molten zinc at the immersion end of the zinc kettle, carried, submerged, through the zinc kettle, and finally withdrawn at the bright end of the kettle. The apparatus shown therein for confining the flux to but one portion of the surface of the molten zinc bath comprises a pair of dams disposed transversely across the upper part of the kettle, each extending inwardly and oppositely from the opposite edges of the kettle and being of such length that their inner ends are closely adjacent, but so spaced that the shanks of the article supporting hooks may pass therebetween. Such opening between the dams permits some of the flux to pass therethrough from

2

the flux-covered portion of the surface of the molten zinc bath to the bright end of the kettle. Also, the shanks of the supporting hooks tend to drag some of the flux through such opening.

The present invention contemplates apparatus for confining a flux or similar layer to one portion of the surface of a body of liquid coating medium, while permitting supporting means for the articles to be coated to pass therethrough; and particularly a flux dam for use in a galvanizing kettle which may form part of an automatic galvanizing system of the general nature of that disclosed in the above-mentioned application.

More specifically, the present invention contemplates a flux dam or similar restrictive and confining apparatus comprising a pair of dams which extend only slightly below the surface of the liquid coating material and which extend inwardly from opposite sides of the kettle and have auxiliary dams pivotally attached to their inner ends. The auxiliary dams are spring urged into contact with one another in such a manner that they may be separated by the article-supporting means to allow for their passage therebetween but at all other times are in contact with one another serving to prevent any flux from passing between their adjacent ends. Preferably the spring means for normally urging the auxiliary dams into contact with one another are located on the outer sides of the kettle at a place where they will be less subject to the heat from molten zinc in the kettle.

The invention will be further described in connection with the accompanying drawings which show an embodiment of the invention particularly adapted for confining a layer of flux to the immersion end of a galvanizing kettle. However, it is to be understood that such further and detailed description is merely by way of exemplification and the invention is not limited thereby, except to the extent set forth in the appended claims.

In the drawings:

Figure 1 is a plan view of a galvanizing kettle embodying the present invention; and

Figure 2 is a transverse sectional view taken along line 2—2 of Fig. 1.

Referring to the drawings, 1 designates any suitable kettle for holding a bath of molten zinc 2 through which ferrous articles 3 are to be passed for galvanizing. The articles are carried by hooks 4 suspended from any satisfactory, continuously moving, overhead conveying means (not shown).

55 A pair of main dams 5 and 6 is transversely

disposed across the kettle adjacent the immersion end. The dams are positioned opposite one another and extend inwardly from the opposite sides of the kettle. Auxiliary dam members or gates 7 and 8 are mounted upon the inner ends of the dams 5 and 6 by means of brackets 9 and 10, attached to the auxiliary dams, and are pivotally connected thereto by pivot pins 11 and 12. The lower edges of the main dams, as well as the lower edges of the auxiliary dams, extend slightly below the surface of the molten zinc, but not a sufficient distance therebelow to interfere with the free passage beneath them of the articles being galvanized. The upper edges of the main and auxiliary dams extend above the surface of the molten zinc a distance sufficient to maintain a layer 13 of flux on the molten zinc between them and the adjacent ends of the kettle.

The auxiliary dams extend forwardly of the main dams in the direction of travel of the articles through the bath, and normally converge toward one another and have their distal ends contacting one another so as to prevent the passage of flux between them.

The auxiliary dams are maintained in their normal position with their distal ends in contact by spring urged rods 14 and 15, which are, at all times, forcibly urged into contact with their outer faces. The ends of the spring urged rods may be connected to the faces of the auxiliary dams which they contact, or, if desirable, may merely abut such faces. The rods extend from the auxiliary dams through slots 16 and 17 located in the opposite side walls of the kettle above the surface of the molten zinc, and outward through openings in the outer ends of brackets 18 and 19 secured to the outer faces of the side walls of the kettle.

Collars 20 and 21 are secured to the rods just outwardly of the side walls of the kettle. Coil springs 22 and 23 are placed around the rods and are interposed between the collars and the outer ends of the brackets under compression, so that they exert a force on the rods such as to normally maintain the distal ends of the auxiliary dam members in engaging contact.

Thus, as the article-supporting hooks traverse the body of molten zinc, their shanks successively contact the distal ends of the auxiliary dams forcing them apart against the action of the coil springs a distance sufficient to permit the passage of the shanks between them. As the free or distal ends of the auxiliary dams are constantly urged toward one another by the springs, a wiping action is provided on the shanks of the hooks as they pass between the free ends of the dams which removes any flux tending to adhere to them and which otherwise might be carried into the bright end of the kettle.

Although but one form of the invention has been described it is to be understood that various changes may be made in the details of the apparatus without departing from the invention or sacrificing the advantages thereof.

I claim:

1. In galvanizing apparatus including a container for a bath of molten zinc adapted to have a layer of supernatant flux thereon, means for confining supernatant flux to one portion of a bath of molten zinc in the container as articles to be galvanized are being passed therethrough which comprise main dams extending inwardly from opposite sides of the container, auxiliary dams each having one end portion pivotally con-

nected to the inner end of one of the main dams, said main dams and auxiliary dams having their lower edges spaced from the bottom of the container a distance sufficient to permit articles to be coated to pass thereunder, and spring means for urging the distal ends of the auxiliary dams into contact, said spring means comprising spring mountings on the outer surfaces of the opposite side walls of the container, and members extending from said spring mountings through apertures in the sides of the container to abutting relation with the auxiliary dams.

2. In a metal coating apparatus including a container for molten metal adapted to have a supernatant layer of flux thereon, means for confining flux to one portion of the molten metal as articles are being passed horizontally therethrough which comprises damming means extending from a side wall of the container toward the opposite side wall, said damming means extending upwardly from the normal level of the interface between the molten metal and a supernatant layer of flux, said damming means comprising a fixed portion and a gate portion movable horizontally relative to the fixed portion in a direction transverse of the adjacent part of the fixed portion to permit passage of article-supporting means past the damming means and simultaneous advancement of the articles horizontally through the molten metal, said relatively movable gate portion being yieldably restrained against horizontal movement relative to the fixed portion.

3. Metal coating apparatus as set forth in claim 2 in which the relatively movable gate portion of the damming means is hinged to the fixed portion about a vertical axis.

4. Metal coating apparatus as set forth in claim 2 in which the means yieldably restraining the relatively movable gate portion of the damming means includes spring means.

5. Metal coating apparatus as set forth in claim 2 in which the damming means is spaced from the bottom of the container a distance sufficient to permit the passage of articles being coated thereunder.

6. Metal coating apparatus as set forth in claim 2 in which the means yieldably restraining the relatively movable gate portion of the damming means is in part mounted on the side of the container, bears against the relatively movable portion of the damming means and includes spring means mounted outside of the container.

7. In a metal coating apparatus including a container for molten metal adapted to have a supernatant layer of flux thereon, means for confining flux to one portion of the molten metal as articles are being passed horizontally therethrough which comprises damming means extending inwardly from opposite edges of the container and upwardly from the normal level of the interface between the molten metal and a supernatant layer of flux, the damming means extending inwardly from each of the opposite sides of the container comprising a fixed portion and a gate hingedly connected to the fixed portion about a vertical axis, the distal edges of said gates being positioned sufficiently close to one another to cooperatively maintain flux on the molten metal behind the damming means, said gates being movable about their hinged connection to the respective fixed portions of the damming means in a forward direction to permit passage of article-supporting means past the damming means and simultaneous advancement of

articles horizontally through the molten metal, and means yieldably restraining said gates against forward movement.

8. Metal coating apparatus as set forth in claim 7 in which the distal edges of the gates normally contact one another and the means for yieldably restraining the gates against forward movement include spring means.
